UNITED STATES PATENT OFFICE.

GEORGE BENJAMIN TAYLOR, OF BIRMINGHAM, ENGLAND.

BENCH FOR SUPPORTING AND MEASURING BAR OR TUBE LENGTHS AND FOR FEEDING SAME TO CUTTING-OFF MACHINES.

1,263,148.

Specification of Letters Patent. Patented Apr. 16, 1918.

Application filed December 26, 1916. Serial No. 139,019.

To all whom it may concern:

Be it known that I, GEORGE BENJAMIN TAYLOR, subject of the King of Great Britain, residing at Bartholomew street, Birmingham, in the county of Warwick, England, have invented certain new and useful Improvements in Benches for Supporting and Measuring Bar or Tube Lengths and for Feeding Same to Cutting-Off Machines, 10 of which the following is a specification.

The invention provides the hereinafter described and claimed improvements in and connected with a bench for supporting and measuring a bar or tube length and for feeding same to a cutting off machine as, for instance, one described in the specifications of prior British Letters Patent Nos. 25,233 of 1910 and 27,487 of 1913 to which the bar or tube needs to be accurately centered to the 20 plurality of cutters.

The bench according to the invention is a rigidly built structure adjustable vertically to wholly raise or lower it and provided with devices for length measurement of the bar supported and to be fed, which devices include a clamp attached to the bar to be measured and adapted to be moved to a different position on the bar for each measure. The bar rests upon rollers disposed in fixed bearings of the bed, some of which rollers are positively revolved by hand operated means, said bar toward its forward end being frictionally gripped by a pair of rollers giving a positive feed. A cam action adjusts the 30 height of the bed which normally lowers by its own weight if the cam action is relieved. The measuring devices comprise, in greater part, a rod secured to the bed, and two stops mounted thereon, a forward and fixed stop, 40 and a rear and adjustable stop, the rod being set out with length measures.

A desirable arrangement of the invention is diagrammatically illustrated by the accompanying drawings.

Figure 1 and Fig. 1^a are a front elevation,

Fig. 2 and Fig. 2^a are a plan,

Fig. 3 is a front end elevation, and

Figs. 4 and 5 are details of the clamp.

The bar or tube to be cut up rests upon five rollers *a*, *b*, *c*, *d*, and *e* disposed in fixed

bearings at distances apart for the full length of the structure, the forward rollers *a* and *b* being positively revolved. The shaft of the roller *b* is also the shaft of the hand 55 wheel *b*², so that by rotation of the hand wheel said roller *b* is revolved. The roller *a* is connected to the shaft of the roller *b* by the chain gear, *a*², and is therefore also revolved by the hand wheel *b*². The rollers *c*, 60 *d* and *e* are followers revolved by the feed of the bar. The peripheries of all the rollers are slightly V'd to provide central seatings thereon for the bar.

The forward roller *a* is the lower one of a 65 pair whose upper roller, *a*³, is supported by a vertically movable frame, *a*⁴, riding upon supporting posts *a*⁵ *a*⁶ and traversed by a hand operated screw *a*⁷, the bar *x*, indicated in Fig. 3, being frictionally gripped between 70 the pair of rollers to put the necessary positive feeding pressure onto the roller *a*. The supports, *a*⁵, *a*⁶, for the frame, *a*⁴, are carried by an underframe, *a*⁸, adapted to rock at *a*⁹ on a pivoting to the bed, *y*, of the 75 machine so that said frame can make a slight angular movement to accommodate inaccuracies in the formation of the bar gripped by the pair of rollers *a* *a*³, said frame however being generally supported by 80 a portion of it resting upon a part *y*² of the bed.

All the lower rollers are supported upon the bed *y* which is bodily adjustable in a vertical direction to centralize varying diameters of bars to the axis of the machine. Said bed is provided by two channel sectioned lengths *y*³ *y*⁴ set opposite and parallel with their channelings outward and the rollers *a*, *b*, *c*, *d*, and *e* disposed in the space *y*⁵ 90 between the channelings, the bottoms of the channelings, now disposed vertically, forming the necessary bearings for the roller shafts. The two channel-sectioned lengths are effectively distanced apart by distancing 95 pieces, *v*, *w*, through which transverse pulling up bolts pass, so that said lengths are held together quite rigidly both longitudinally and transversely. The space *y*⁵ also accommodates the upper ends, *f*², *g*², of two 100 pillars, *f*, and, *g*, which are adapted to slide vertically in sockets, *f*³, *g*³, of underframes,

s, and, *t*, secured to any suitable foundation for supporting the bench, said upper ends being attached to the channelings by cross bolts *f*⁴ *g*⁴, the latter preferably working in 5 a slot of the pillar's upper end. The underframes *s* and *t* are disposed one near each end of the bed, and they and a middle frame *m* form a support for a longitudinal rocking shaft *n* revolved from the collar *n*² and 10 carrying at *n*³ *n*⁴ two cams adapted by their peripheries to contact blocks *n*⁵ *n*⁶ suitably bolted across the undersides of the lower flanges of the two channel sectioned lengths. The cams form supports for the whole of 15 the weight of the bed *y* and the parts it carries, and they provide the means for simultaneously lifting the bed at both ends to the same extent so that the plane of the bed is always in the horizontal plane, while 20 the pillar and socket engagements *f*, *f*², *g*, *g*² guide the truly vertical movement.

Extending along the one side of the bed *y* parallel therewith is a fixed measuring and stop carrying rod *h* set out with length 25 measures as indicated by Figs. 2 and 2^a. This rod has end bearings at *h*² *h*³ within brackets suitably bolted to the channel sectioned length *y*³. Two stops *i* and *j* are fitted to this rod, the former one a fixture, 30 and the latter adjustable along said rod. The adjustable stop *j* is adapted for being clamped on the rod, and is set thereon relative to the fixed stop *i* to the measure of the bar length to be cut off plus the amount of 35 metal cut away by the tools in cutting off and plus the length of a clamp extension *o*, hereinafter described, which measure is then the distance between the two stops. Said two stops when nearest are always distanced 40 the length of said clamp extension *o*, as will be clear from Figs. 1 and 2.

The connecting piece between the bar *x* to be measured and the stops *i* and *j* is a clamp *l*, Figs. 4 and 5, adapted to be firmly but detachably attached to the bar, *x*, by the two screw pins *l*² *l*³, said attachment being adjusted by the adjustable positioning abutment *l*⁴ of said clamp. This clamp carries the extension *o* adapted to contact the two 55 stops *i* and *j*, said extension being resilient in its touch with the adjustable stop *j*. The clamp is fixed to the bar *x* while its extension *o* is contacting the back stop *j*, and then the bar is fed up by the rollers *a*, *b*, *c*, *d*, and 60 *e*, through the operation of the hand wheel *b*², until the extension *o* contacts the forward stop *i*, which gives the necessary projection of the bar into the cutting off machine to cut off the desired length from the 65 bar, the clamp *l* being moved back to a different part of the bar while each length is being cut off ready for the bar to be fed up again to the measure between the two stops *i* and *j*. The resilient or spring contact of

the extension *o* is provided by a plunger, *o*², 65 working in a sleeve, *l*⁵, of the clamp and spring operated in one direction by a coiled spring, *o*³, placed in compression between the pin, *l*², of the clamp and the plugged end, *o*⁴, of the plunger, and positively operated in the other direction by a screw nut, *o*⁵, engaging the other end of the plunger and abutting against the adjacent end of the sleeve, said nut being loosened so that the spring *o*³ may be fully operative when the 70 clamp is being placed on a different part of the bar with its end *o*⁴ hard up to the back stop *j*, during which time the bar is stationary, which nut *o*⁵ is afterward tightened up to a feeling tightness only, in this way 75 providing so that the measure of bar fed shall be always accurate to the measure between the two stops *i* and *j*. The contact of the extension *o* with the stops is always at its ends only, and the spring pressure always insures touch of said extension at the end *o*⁴.

Having now described my invention what I claim and desire to secure by Letters Patent is:—

1. A bench for the purpose described comprising a rigidly constructed bed, means applied to the bed to centrally support a bar or tube length, a length measuring rod carrying stops fitted to said bed, and a clamp adapted to be detachably connected to the bar or tube length to be measured to coöperate with the length measuring rod, substantially as described.

2. A bench for the purpose described comprising a rigidly constructed bed, rollers applied to said bed to centrally support a bar or tube length and to feed same forward and some of which are positively revolved by hand operated means, a length measuring rod carrying stops fitted to said bed, and a clamp detachably attached to the bar or tube length to be measured to coöperate with the length measuring rod, substantially as described.

3. A bench for the purpose described comprising a rigidly constructed bed, rollers applied to said bed to centrally support a bar or tube length and to feed same, a forward pair of which are adapted to frictionally grip the bar or tube, and a number of which are positively revolved by hand operated means, a length measuring rod carrying stops fitted to said bed, and a clamp detachably attached to the bar or tube length to be measured to coöperate with the length measuring rod, substantially as described.

4. A bench for the purpose described comprising a rigidly constructed bed, pillar and socket and cam supports to said bed by which same can be adjusted, means applied to the bed to centrally support a bar

or tube length, a length measuring rod carrying stops fitted to said bed, and a clamp detachably attached to the bar or tube length to be measured to coöperate with the 5 length measuring rod, substantially as described.

In testimony whereof I have hereunto set

my hand in presence of two subscribing witnesses.

GEORGE BENJAMIN TAYLOR.
